UNITED STATES PATENT OFFICE.

OLIVER H. HENRY, OF CHICAGO, ILLINOIS.

WRENCH.

1,333,174.

Specification of Letters Patent.

Patented Mar. 9, 1920.

Application filed March 4, 1919. Serial No. 280,585.

To all whom it may concern:

Be it known that I, OLIVER H. HENRY, a citizen of the United States, residing at Chicago, in the county of Cook and State of Illinois, have invented certain new and useful Improvements in Wrenches, of which the following is a specification.

This invention relates in general to wrenches and has particular reference to a pipe wrench, wherein the various adjustments thereof may be quickly obtained, while the construction is such as to facilitate the gripping of pipes of various shapes.

One object of this invention is the production of a pipe wrench which includes a movable jaw carried upon the fixed jaw, the movable jaw being of an angular construction, whereby the fixed jaw may grip an element at the angle of the movable jaw.

Another object of this invention is the production of a pipe wrench wherein a socket is provided in the side of the fixed jaw for the reception of a spring, the spring being connected to the movable jaw and also to the fixed jaw, whereby the movable jaw will move to a firm engagement with an article inserted between the jaws, thus allowing the wrench to be easily operated with one hand.

One practical form of construction and assembly of the present invention will be hereinafter described and is illustrated in the drawings, in which:-

Figure 1 is a detail perspective view of the wrench illustrating in dotted lines the manner in which the device is used.

Fig. 2 is a fragmentary elevation of the wrench a portion of the movable jaw being shown in section.

In the preferred embodiment of the present invention about to be described, 5 indicates the fixed jaw which has the tapering shank extending therefrom which constitutes the handle 6. Thus it will be seen that the fixed jaw and the handle are integral. The fixed jaw 5 has a curved inner surface provided with the gripping teeth 7, it being noted that the fixed jaw 5 tapers toward its end.

The movable jaw 8 comprises a body 9 having a projection 10 extending at right angles thereto, thus forming a substantially L-shaped structure to provide an angular receiving portion at the inner portion of the movable jaw. The body 9 of the movable jaw is also provided with gripping teeth 11

upon its inner surface. The projection 10 is bifurcated as shown at 12, thus providing a pair of bearing ears 13 carried in parallel relation. The bifurcation 12 is made to provide the slanting inner wall 14 to accommodate the pivotal movement of the fixed jaw 5.

The fixed jaw is inserted between the ears 13 and the bearing pin 15 is passed through the ears 13 and also through the fixed jaw 5, thus pivotally mounting the movable jaw upon the fixed jaw.

In order to force the movable jaw toward the fixed jaw, the spring 16 surrounds the pin 15 and has fingers 17 extending therefrom. The fixed jaw 5 is provided with a socket 18 in one side surface thereof it being noted that this socket 18 is open upon one side thereof as at 19 to communicate with one edge of the fixed jaw as shown in Fig. 2. One finger 17 of the spring 16 is fixed in engagement with the fixed jaw 5 adjacent the inner end of the socket 18. The remaining finger 17 is fixed by a projection 17' 80 thereon in engagement with one of the ears 13 of the movable jaw. Therefore it will be noted that the tension of the spring 16 will swing the movable jaw to the position shown in Fig. 2 at which time the end of the fixed 85 jaw will be adjacent the body of the movable jaw.

When the device is in use, the body of the movable jaw may be placed in engagement with the pipe and then by pulling upon the body of the movable jaw it is obvious that it will be swung away from the fixed jaw, thus allowing the pipe to be moved into the angle of the movable jaw and at this time by a discontinuation of such pulling upon the 95 movable jaw, it will be noted that the tension of the spring will bring the movable jaw into firm engagement with the pipe and at this time the fixed jaw will also be engaging the pipe as indicated in Fig. 1. Then by pulling upon the handle 6 as indicated by the position of the hand in dotted lines in Fig. 1, the jaws will be urged toward each other and thus the pipe will be more firmly gripped. The teeth will also grip the pipe 100 to hold the wrench from slipping when such a pressure is being applied thereto. Because of the angular construction of the movable jaw, the wrench will grip not only round pipes, or round structures, but will 110 easily grip articles which are square or are possessed of more sides of a flat nature.

A provision of the socket in the side of the fixed jaw allows the spring to be easily carried without injury and without pinning between the two jaws. As the socket is 5 open upon one side, as above specified, to communicate with the side edge of the fixed jaw which has the teeth thereon, the finger 17 of the spring 16 having the projection 17' may swing out from the socket when the 10 movable jaw is being swung away from the fixed jaw.

From the foregoing description it will be obvious that a very simple pipe wrench has been provided which because of the connection of the movable jaw to the fixed jaw allows the device to be easily operated by one hand. Furthermore because of the angular construction of the movable jaw, the tapered end of the fixed jaw, articles of various shapes may be easily gripped therebetween. Also the provision of the socket provides sufficient room for the spring, although the socket is formed to allow the spring to easily move as the movable jaw 25 is being swung although when the jaws are released the movable jaw will bring an article so engaged in to position between the fixed jaw and the movable jaw as will allow the article to be easily gripped.

The foregoing description and accompanying drawings have reference to what might be considered to be the preferred or approved form of my invention. I desire it to be understood that I may make such 30 changes in the construction, combination and arrangement of parts, materials, dimensions, et cetera, as may prove expedient and fall within the scope of the appended claim.

Having thus fully described my invention what I claim as new and desire to secure by 40 Letters Patent, is:—

In a wrench of the class described, the combination of a fixed solid jaw having a handle extending therefrom, said fixed jaw having a socket formed in one side thereof, 45 the socket having an open side communicating with one edge of the fixed jaw, an enlarged L-shaped movable jaw having a bifurcated end embracing said fixed jaw, a bearing pin passing through the jaws, a 50 coiled spring carried upon said pin and being positioned within said socket, said spring having elongated fingers extending therefrom toward opposite ends of the socket, one of said fingers being fixed upon 55 said fixed jaw and the remaining finger upon the movable jaw, and said movable jaw normally extending for a considerable distance to one side of the fixed jaw, whereby the operator may grip the handle and by 60 changing the position of the wrench upon the object to be gripped for turning, one of the fingers will move to the side opening of said socket for allowing the swinging of said movable jaw, whereby the objects may 65 be moved to the inner portion of the movable jaw in the path of movement of the fixed jaw when the handle of the wrench is swung in one direction.

In testimony wherof I affix my signature 70 in presence of two witnesses.

OLIVER H. HENRY.
